[57] **CLAIM**

The ornamental design for protective pocket for the dialing knobs of the printhead of a labelling apparatus, as shown and described.

DESCRIPTION

FIG. 1 is a perspective view of a protective pocket for the dialing knob of the printhead of a labelling apparatus showing my new design with the labelling apparatus being illustrated in broken lines for environmental purposes only;

FIG. 2 is a front elevational view of my new design;

FIG. 3 is a cross-sectional view taken along line 3—3 in FIG. 2;

FIG. 4 is a cross-sectional view taken along line 4—4 in FIG. 2;

FIG. 5 is a top plan view of my design; and

FIG. 6 is an elevational view taken from the right hand side of FIG. 2.
